UNITED STATES PATENT OFFICE.

JOSEPH WILCOX, OF ATHOL, MASSACHUSETTS.

DESIGN FOR A COMB.

No. 38,847.

Specification for Design.

Patented Oct. 8, 1907.

Application filed August 30, 1907. Serial No. 390,834. Term of patent 3½ years.

To all whom it may concern:

Be it known that I, JOSEPH WILCOX, a citizen of the United States, residing at Athol, in the county of Worcester and State of Massachusetts, have invented a new, original, and ornamental Design for Combs, of which the following is a specification, reference being had to the accompanying drawing, forming part thereof.

The figure is an elevation of a comb showing my new design.

I claim

The ornamental design for a comb, as shown.

JOSEPH WILCOX.
